SWINGING REFRIGERATOR SHELF

Floyd R. Eck, Des Plaines, Ill., assignor to Motor Products Corporation, Detroit, Mich., a corporation of New York

Application November 6, 1950, Serial No. 194,227

1 Claim. (Cl. 312—326)

1

The present invention relates to a swinging refrigerator shelf and more particularly to a swinging shelf which is adapted to be resiliently retained in retracted position and which contains covered containers for leftovers.

It is an object of the present invention to provide a swinging shelf for a refrigerator provided with a supporting hinge of novel construction.

It is a further object of the present invention to provide a refrigerator shelf having a supporting hinge including torsion spring means for biasing the shelf toward retracted position.

It is a further object of the present invention to provide a swinging shelf for a refrigerator including adjustable means for biasing the shelf toward retracted position.

It is a further object of the present invention to provide a refrigerator having a shelf, a fixed storage compartment located above the shelf at one side of the refrigerator, a swinging shelf located above the shelf at the other side of the refrigerator, the space between said fixed storage compartment and said swinging shelf being sufficient to permit the reception of tall items such as bottles, the swinging shelf being designed to permit outward swinging movements to afford access to the swinging shelf without disturbing items disposed between the swinging shelf and the fixed storage compartment.

It is a further object of the present invention to provide a refrigerator having a storage compartment therein, a swinging shelf in said compartment including hinge means for mounting said shelf for swinging movement about a vertical axis disposed adjacent the front of said compartment to permit swinging movement of the shelf out of the compartment to afford access for storage and removal of articles in the space behind the shelf.

It is a further object of the present invention to provide a swinging shelf of wire construction affording access to the side of the shelf exposed when the shelf is in retracted position, and also affording access to the side of the shelf exposed when the shelf is in extended position.

Other objects and features of the invention will become apparent as the description proceeds, especially when taken in conjunction with the accompanying drawings, wherein:

Figure 1 is a front elevational view of a refrigerator including the improved swinging shelf illustrated, with the usual front door closure removed.

Figure 2 is an enlarged front elevational view of the swinging shelf.

2

Figure 3 is a fragmentary section on the line 3—3, Figure 2.

Figure 4 is a plan view of the shelf showing its retracted position in full lines and its extended position in dotted lines.

Figure 5 is a section on the line 5—5, Figure 2.

Referring now to the drawings there is illustrated in Figure 1 a refrigerator 10 having a storage compartment 12 provided with a plurality of shelves including a fixed shelf 14 defining thereabove a relatively large storage space 16. At one side of the refrigerator and spaced substantially above the shelf 14 is a storage member 18 which is herein illustrated as a retractable compartment but which might be any other type of storage member such for example as a separate shelf.

Located at the opposite side of the space 16 is a swinging refrigerator shelf indicated generally at 20. It will be observed that a substantial space is provided between the member 18 and the shelf 20 to permit storage of relatively tall articles on the shelf 14 with their upper portions extending into the space between the member 18 and the shelf 20.

Referring now to Figures 2, 3 and 4, the refrigerator shelf comprises essentially a bottom border wire 22, a top border wire 24, vertical wires 25, 26, and 27 interconnecting the top and bottom border wires, and a plurality of relatively small wires 28 extending across and secured to the underside of the bottom border wire 22 to form a floor for the shelf. Inasmuch as the relatively small wires 28 are secured to the lower surface of the bottom border wire 22, the bottom border wire 22 constitutes a bordering abutment serving to retain articles on the shelf. If desired, the wires 22 and 24 may carry flat decorative trim strips 29 at the front.

It will also be observed that due to the spacing and location of the vertical wires 25, 26, and 27, the entire front of the shelf construction is open when it is in retracted position and substantially the entire side of the shelf construction is open to permit ready insertion of leftovers' containers, as indicated at 30, 31 and 32.

Moreover, it will be observed that the containers 30, 31 and 32 are shaped to take full advantage of the space provided and fit in such a manner as to occupy substantially the entire horizontal area 50 of the shelf construction.

The shelf construction is provided with a vertical hinge construction adjacent its front corner, by means of which it is hinged to the inner wall of the storage compartment of the refrigerator. In order that forward swinging

movement of the shelf about this hinge may take place without interference with tall articles stacked so as to occupy the space between the fixed storage member 18 and the swinging shelf 20, the inner side of the shelf construction is curved substantially concentrically with the hinge axis, the portions of the border wires indicated at 34, as best seen in Figure 4, being curved for this purpose.

A particular form of hinge mounting is provided which comprises a mounting plate 36 having a pair of vertically spaced axially aligned cylindrical journals 38 and 39 formed thereon. The plate 36 is secured to a side wall of the storage compartment of the refrigerator by suitable means such for example as the screws indicated at 40. The hinge is completed by a support wire 42 having the configuration best illustrated in Figure 3. The wire 42 includes two spaced horizontal portions 44 and 46 interconnected by a vertical portion 48. At the free ends of the horizontal portions 44 and 46 there are provided depending hinge pin portions 50 and 52 respectively. The hinge pin portions 50 and 52 are each provided adjacent their free ends with supporting collars 54 and 56 respectively. The collars serve as abutments and rest upon the upper ends of the journals 38 and 39 respectively. It will be observed that the hinge construction is so arranged that the upper journal 38 is located beneath the upper border wire 24, and the lower journal 39 is located substantially below the lower border wire 22. The substantial spacing between the journals thus afforded results in improved rigidity of the shelf.

Means are provided which operate to urge the shelf toward the retracted position shown in full lines in Figure 4. This means is best illustrated in Figure 5. To accomplish the foregoing result the journal 38 at its lower end is provided with a bushing 60 which is internally threaded. The bushing has a radially extending flange 62 adapted to seat against the lower end of the journal 38. Thus the bushing 60 may be pressed into the lower end of the journal 38 and will be firmly retained therein against rotation. Extending through the bushing is a threaded adjusting screw 64 which is provided with a recess 66 at its outer end for the reception of a screw driver. The inner end of the screw is provided with a transverse slot 68.

The lower end of the hinge pin 50 has a V-shaped notch 70 therein which terminates in a straight-sided slot 72. Extending between the lower end of the hinge pin 50 and the upper end of the adjusting screw 64 is a torsion spring 74, which as illustrated is a helical coil spring the ends of which are extended and bent to extend transversely or diametrically across the spring. One end of the spring is received in the slot 68 in the adjusting screw and the other end of the spring is received within the slot 72 of the hinge pin 50. The V-shaped notch 70 insures that the upper transverse end of the spring will be guided into the slot 72 when the parts are assembled as shown in Figure 4. In order to retain the adjusting screw 64 in adjusted position, there is provided a lock nut 16. While rotation of the adjusting screw 64 will of course effect some vertical movement thereof, its primary adjusting movement is in rotation and it will adjust the torque provided by the spring 74 on the hinge pin 50.

The hinge mounting of the shelf permits the shelf to be swung to the dotted line position shown in Figure 4 at which time access is afforded to the open top of the construction as well as to the open space between the top and bottom border wires. When the shelf is in the retracted position illustrated in full lines the open front construction permits the insertion of the containers 30, 31 and 32 without the necessity of swinging the shelf to its extended position. Moreover, the shelf may be swung forwardly to afford access to the space at the rear of the storage compartment behind the shelf. Thus, by employing the swinging shelf as described the substantial space remaining behind the shelf may be employed for the storage of relatively large articles such for example as bottles or the like.

The drawings and the foregoing specification constitute a description of the improved swinging refrigerator shelf in such full, clear, concise and exact terms as to enable any person skilled in the art to practice the invention, the scope of which is indicated by the appended claim.

What I claim as my invention is:

In a refrigerator having a storage compartment, a swinging shelf adapted to receive a plurality of small containers for left-overs, said shelf having a continuous bottom border wire, a plurality of straight horizontal bottom wires secured to the underside of said bottom border wire whereby said bottom border wire constitutes a raised guard abutment, a continuous top border wire overlying said bottom border wire, the space enclosed within said top border wire being entirely unobstructed to provide top access to said shelf, said top border wire being spaced above said bottom border wire a distance sufficient to provide for movement of left-over containers therebetween, hinge means adjacent a front corner of said shelf for mounting said shelf for outward swinging movement on a side of the storage compartment, vertical posts connecting said top and bottom border wires and located at the rear and hinged side of said shelf, and a single additional vertical post connecting said top and bottom border wires and located adjacent the side of said shelf remote from the hinged side thereof, the space between said top and bottom border wires at the front of said shelf being entirely unobstructed to provide access to containers on said shelf through the space between said top and bottom border wires at the front of said shelf when said shelf is swung inwardly of the refrigerator compartment.

FLOYD R. ECK.
